F. NOVESS.

POST.

APPLICATION FILED AUG. 26, 1913.

1,134,897.

Patented Apr. 6, 1915.

UNITED STATES PATENT OFFICE.

FRANK NOVESS, OF YPSILANTI, MICHIGAN.

POST.

1,134,897.

Specification of Letters Patent.

Patented Apr. 6, 1915.

Application filed August 26, 1913. Serial No. 786,771.

To all whom it may concern:

Be it known that I, FRANK NOVESS, a citizen of the United States, residing at Ypsilanti, in the county of Washtenaw and State of Michigan, have invented new and useful Improvements in Posts, of which the following is a specification.

This invention relates to fence posts and more particularly to corner posts.

One of the principal objects of the invention is to provide a novel type of bracing means which will effectively support the post against strains extending at different angles.

Another object of the invention is to provide novel means for bracing the post, for adjusting the braces and for preventing the braces from lifting the post out of its base.

Further objects of the invention will appear as the following description is read in connection with the accompanying drawing, which forms a part of this application, and in which:—

Figure 1 is a perspective view. Fig. 2 is an enlarged detail vertical sectional view taken through one of the braces and through one leg of the supporting base. Fig. 3 is a detail bottom plan view with parts broken away to show the connection of the adjusting rod with the locking plate, and the means for preventing the post from lifting out of the base. Fig. 4 is a detail plan view of the brace abutment.

Referring more particularly to the drawing, 1 represents a cement base which is substantially L-shape and preferably suitably reinforced so as to eliminate fracture. Each leg of the base is provided with a longitudinal groove or channel 2 which terminates in an enlarged recess 3 at the end of the leg and where the legs join or at the apex of the angle a recess or socket 4 is produced for the reception of the post 5. This post is preferably constructed of iron pipe of suitable diameter and has a cross pin 6 projecting from opposite sides thereof and arranged to engage in a groove 7 formed in the under-side of a locking plate 8 which is secured to the base by bolts 9 embedded in the base, as shown, and surrounds the post 5. This pin being in engagement with the groove prevents the post from turning in the socket and also from lifting out of the socket.

In order to hold the post in vertical position there is secured to the post mid-way between its length a suitable abutment 10 having right angularly arranged faces 11, each provided with a projecting stud 12 for a purpose to be hereinafter described. Slidably mounted in the recess 3 are long, longitudinally channeled blocks 13 having angular brace abutting faces 14 provided with projecting studs 15 similar to the studs 12 on the abutments 10. The studs 12 and 15 are arranged to enter the ends of suitable braces 16 extending between the blocks 13 and the abutment and held in place by adjusting rods 17 lying in the channels 2 and passing through each block 13 where they are provided with an adjusting nut, as shown. The opposite end of each rod is arranged in the form of an eye 18 which is engaged by one of the bolts 9. Therefore, as the nut 19 on the rod is tightened the block 13 will be moved toward the post and the brace will push the upper end of the post into vertical position. Each post is preferably provided with a strip 20 having a plurality of lugs arranged thereon to prevent the fence wire from dropping. By loosening the nuts upon the bolts 9 the entire post, braces and adjusting rods may be removed from the base.

As shown, the abutment 10 is provided with a grooved semi-circular collar 21 which is engaged by a U-bolt 22 for clamping the abutment to the post. This method of attaching the abutment provides for its convenient vertical adjustment when necessary.

What is claimed is:—

A fence structure comprising an L-shaped base having grooves in its upper surface, a plate secured to the apex of said base by bolts, a post passing through said plate and having means connected with said plate to prevent the post from turning, abutments slidably mounted in the grooves in said base and adjustably connected by rods to said bolts, a vertically adjustable abutment mounted on the post, and braces extending between the sliding abutments in the base and the vertically adjustable abutment.

In testimony whereof I affix my signature in presence of two witnesses.

FRANK NOVESS.
